(57) **CLAIM**

The ornamental design for a machine body of floor washing appliance as shown and described.

DESCRIPTION

1. Machine body of floor washing appliance
2. Machine body of floor washing appliance

1.1 : Front

1.2 : Back

1.3 : Left

1.4 : Right

1.5 : Top

1.6 : Bottom

1.7 : Perspective

1.8 : Perspective

2.1 : Front

2.2 : Back

2.3 : Left

2.4 : Right

2.5 : Top

2.6 : Bottom

2.7 : Perspective

2.8 : Perspective

1.1 is a front view of a first machine body of floor washing appliance, 1.2 is a back view thereof, 1.3 is a left view

(Continued)

thereof, **1.4** is a right view thereof, **1.5** is a top view thereof, **1.6** is a bottom view thereof, **1.7** and **1.8** are two perspective views thereof; **2.1** is a front view of a second machine body of floor washing appliance, **2.2** is a back view thereof, **2.3** is a left view thereof, **2.4** is a right view thereof, **2.5** is a top view thereof, **2.6** is a bottom view thereof, **2.7** and **2.8** are two perspective views thereof.
